ABSTRACT

Roll changing means for a four-high rolling mill for automatically and rapidly changing top and bottom working rolls and top and bottom backup rolls without necessitating the use of a crane by combining a working roll changing truck and a backup roll changing truck in a double-sled shifted sidewise manner.

SHEET 4 OF 4

FIG. 4

truck for carrying the working roll changing truck 19 and the unused backup rolls 2' and 3'. The truck 26 is transversely movable sidewise to the roll axis. The truck 26 is provided with sliding surfaces 27 and 28 for carrying the backup roll for sliding movement in the direction of roll axis, and with a plurality of rails 29 for carrying the working roll changing truck 19 for movement in the direction of roll axis. The backup roll-changing truck 26 is further slidably mounted on supporting pedestals 31 and 31' and can be transversely moved in the direction perpendicular to the roll axis by hydraulic cylinder 30. The numerals 32 and 32' show stoppers for the trucks 26 provided at the opposite ends of the supporting pedestals 31 and 31', and 33 and 33' show intermediate stoppers which can be adjusted in position by a hydraulic cylinder 34 and is adapted to limit the transverse travel of the backup roll changing truck 26. The numeral 35 shows a changing sled for carrying the bearing chock 7 of the bottom backup roll 3, 36 a frame for connecting the operating side sled 35 and a sled on the drive side (not shown), and 37 an intermediate supporting pedestal for guiding the top and bottom backup rolls 2 and 3 from the rolling mill stand 1 to the backup roll changing truck 26 when the rolls are being changed. The pedestal 37 is so arranged that its upper surface aligns with the lower surface of said sled 35 and the upper surface of the truck 26. The numeral 38 shows a hydraulic cylinder for moving the top and bottom backup rolls 2 and 4 from and into the rolling mill stand 1, 39 a hook for connecting the hydraulic cylinder 38 and the sled 35, 40 an arm extending from the lower side of the working roll changing truck 19, and 41 a hook rotatably mounted on said arm 40 for connecting the working roll-changing truck 19 with the sled 35. By this hook 41, the working roll-changing truck 19 can be moved rearwardly simultaneously when the top and bottom backup rolls 2 and 3 are moved outwardly from the rolling mill stand 1. The numeral 42 shows a hydraulic cylinder for effecting the vertical movement of the floor plate 20, and 43 shows shunt rails provided on the base below the floor plate 20 at a lever the same as the rails 29 for carrying the truck 19. The shunt rails are provided for retracting the working roll-changing truck 19 from the backup roll-changing truck 26 when the backup rolls 2 and 3 are being changed. The numeral 44 shows shunt rails provided at a level same as the rails 22 for carrying the traction car 18. The shunt rails 44 are provided for retracting the car 18 and the working rolls 4 and 5 rearwardly. The numeral 45 shows a stool adapted to be inserted between the backup rolls 2 and 3 after the working rolls 4 and 5 are retracted from the rolling mill stand 1, 46 a stool inserted between the top and bottom backup rolls 2' and 3', and 47 a hook for connecting the traction car 18 and the bottom working roll 5.

When it is desired to remove and replace the working rolls 4 and 5, the top backup roll 2 is upwardly moved by the balance cylinder (not shown) through the carrier beam 10 to provide a space required to change the rolls. Then, the rails 14 are moved upwardly by the hydraulic cylinders 16 until they engage with the stoppers 15, and the top and bottom working rolls 4 and 5 are placed on the rails 14. In this position, the upper surface of the rails 14 and the upper surface of the rails 21 of the truck 19 align with each other. Thereafter, the top and bottom working rolls 4 and 5 with the bearing chocks 8 and 9 are slidably moved by the traction car 18 along the rails 14 onto the rails 21 from the rolling mill stand 1. Prior to this step, a new set of top and bottom working rolls are placed on the rail 21' of the working roll changing truck 19. (The drawings show a position in which the backup rolls are being changed, so that the stool 45 is disposed on the rail 21'. Further, a new pair of backup rolls 2' and 3' are disposed on the sliding surface 27 of the truck 26. However, when only the working rolls are to be changed, they may be omitted and the sliding surface 27 may be left free of rolls). Thus, when the top and bottom working rolls 4 and 5 are completely transferred on the truck 19, the hydraulic cylinder 30 is actuated to move the working roll changing truck 19 together with the truck 26 in the direction perpendicular to the roll axis until the axes of

the new working rolls align with the center of the rolling mill. In this case, in order to determine the transversely transferred position of the trucks, the intermediate stoppers 33 are used. Thus, the truck 26 can only be moved to the position in which it engages with the stoppers 33. Thereafter, the traction car 18 is operated and the new working rolls are moved into the rolling mill stand 1. Then, the changing rails 14 are lowered by the hydraulic cylinder 16 and the backup rolls 2 are returned to its initial position by the balance cylinder (not shown) which acts through the carrier beam 10. Finally, the screw 11 is adjusted and thus the rolling mill becomes ready for operation. The removed working rolls 4' and 5' are transferred by the traction car 18 to a suitable position and from there they are carried by a crane.

15 The operation in which the backup rolls are removed and replaced will now be described. The stool 45 is placed on the rails 21' of the working roll-changing truck 19 and a pair of new backup rolls 2' and 3' with metal chocks are mounted on the sliding surface 27 of the backup roll-changing truck 26. The stool 46 is interposed between the said bearing chocks. When the upper and lower working rolls 4 and 5 are transferred to the working roll changing truck 19 as shown by 4' and 5' in the drawings through the steps of the above-described working roll-changing operation, the hook 47 is disconnected with the traction car 18 placed on the rails 22 and thereafter the hydraulic cylinder 30 is actuated to move the backup roll-changing truck 26 and the working roll-changing truck 19 in the direction perpendicular to the roll axis until the center of the stool 45 aligns with the center of the rolling mill or until the trucks are stopped by the intermediate stopper 33. In this position, the traction car 18 is again operated so as to move the spacer 45 into the rolling mill stand 1 through the intervention of the hook 47. Thereafter, the car 18 is again returned on the rails 22. Then, the rails 14 are lowered by the hydraulic cylinder 16 until the stool 45 is placed on the bearing chocks 7 of the bottom backup roll 3. The top backup roll 2 is further lowered through the carrier beam 10 until its metal chocks 6 rides on said stool 45.

20 40 The removed working rolls 4' and 5' are placed on the working roll changing truck 19 when the stool 45 is being moved into the rolling mill stand 1, and when the backup roll-changing truck 26 is moved with the working roll-changing truck 19 to the position shown in FIG. 3 in which the truck 26 is stopped by the stoppers 32, the rolls 4' and 5' are transferred along the rails 21 of the working roll changing truck 19 and the rails 22 of the floor plate 20 onto the shunt rails 44. Thereafter, the floor plate 20 is lifted by the hydraulic cylinder 42 to provide a space for receiving the truck 19. Then, the top and bottom backup rolls 2 and 3 with bearing chocks are removed as a unit from the rolling mill stand 1 by the hydraulic cylinder 38 which acts through the hook 39 and the sled 35, and are transferred through the intermediate supporting pedestal 37 to the sliding surface 28 of the backup roll-changing truck 26. In this instance, since the work roll changing truck 19 is connected with the sled 35 by the hook 41, the truck 19 is moved on the shunt rails 43 provided below the floor plate 20 simultaneously as the backup rolls 2 and 3 are removed from the rolling mill stand. Therefore, the working roll-changing truck 19 does not interfere with the backup rolls when the rolls are moved onto the truck 26. Thereafter, the hooks 39 and 41 are opened to disconnect the sled 35.

25 45 50 55 60 65 70 75

Then, the intermediate stopper 33 is moved away from the operative position by the hydraulic cylinder 34, and the hydraulic cylinder 30 is actuated to move the backup roll-changing truck 26 until it engages with the stoppers 32'. Thus, the center of the new backup rolls 2' and 3' comes into alignment with the center of the rolling mill. Thereafter, the hook 39 is connected with the changing sled 35' of the new backup rolls 2' and 3', and the hydraulic cylinder 38 is actuated to move the rolls 2' and 3' into the rolling mill stand 1. After the backup rolls are moved into the rolling mill stand, said top and bottom backup rolls 2 and 3 are carried out by a crane, and the backup roll-changing truck 26 is transversely moved until it

engages with the intermediate stopper 32. Thereafter, the hook 39 and the arm 40 are connected with each other, and the hydraulic cylinder 38 is actuated to move the working changing truck 19 onto the backup roll-changing truck 26. The floor plate 20 is then lowered to the original position by the hydraulic cylinder 42. From this position, the removed working rolls 4' and 5' are transferred by the traction car 18 from the shunt rail 43 through the rail 22 to the rail 21 of the working roll-changing truck 19. As the next step, the upper backup roll in the rolling mill stand 1 is lifted by the balance cylinder (not shown) through the carrier beam 10, and the rail 14 is lifted to a predetermined position by the hydraulic cylinder 16. Thereafter, as in the working roll-changing operation, the stool 46 which has been moved into the rolling mill stand is replaced by the top and bottom working rolls 4' and 5' by using the traction car 18. Then, the balance cylinder for the backup roll (not shown) and the balance cylinder 13 for the working roll are actuated, and the screw 11 of the screwdown mechanism is adjusted as required. Thus, the rolling mill becomes ready for operation.

The present invention has been described and illustrated with reference to a preferred embodiment, however, it should of course be understood that the embodiment is merely an example and various changes and modifications may be made without departing from the spirit and scope of the present invention.

We claim:

1. Roll-changing means for a four-high rolling mill comprising means provided in a rolling mill stand in parallel relation with a roll axis for supporting the roll for axial movement when it is removed and replaced, lifting means for placing said roll on said support means when the roll is being removed and replaced, transfer means for axially transferring the roll from and into the rolling mill stand, a working roll-changing truck provided outside the rolling mill stand for carrying used and new working rolls, a backup roll-changing truck for carrying said working roll-changing truck and used and new backup rolls, transverse transfer means for transferring said backup roll-changing truck in the direction perpendicular to the roll axis so as to change the relative position of the used and new backup rolls, means for enabling the transverse transfer means to be used for transversely transferring the working roll-changing truck, and retracting means for retracting said working roll-changing truck in a direction substantially parallel to said roll axis when the backup roll is being changed.

2. Roll-changing means for a four-high rolling mill in accordance with claim 1, in which said lifting means comprises hydraulic cylinders and linkages provided at the opposite sides of the rolling mill stand for vertically moving said support means.

3. Roll-changing means for a four-high rolling mill in accordance with claim 2, in which the transfer means for axially moving the top and bottom work rolls includes a traction car which is arranged so as to move along rails which are provided outside the rolling mill stand and in alignment with roll-changing rails in the rolling mill stand.

4. Roll-changing means for a four-high rolling mill in accordance with claim 3, in which said traction car includes an electric motor and a mechanism for transferring the rotation of the motor, a pinion shaft in the mechanism being arranged to engage with racks provided on the working roll-changing truck and a floor plate.

5. Roll-changing means for a four-high rolling mill in accordance with claim 3, in which the rails along which the traction car moves comprises rails provided on the working roll-changing truck outside the rolling mill stand, rails provided on a floor plate which is behind the working roll-changing truck, and shunt rails provided further rearwardly of said floor plate.

6. Roll-changing means for a four-high rolling mill in accordance with claim 5, in which the transfer means for axially moving the top and bottom backup rolls comprises a hydraulic cylinder, a sled for carrying bearing chocks of the bottom backup roll and a hook for connecting the hydraulic cylinder

and the sled.

7. Roll-changing means for a four-high rolling mill according to claim 6, in which said working roll-changing truck is mounted for movement in the direction of roll axis on the backup roll-changing truck and has on its upper surface two sets of rails for supporting the used and new working rolls and a stool inserted between the top and bottom backup rolls.

8. Roll-changing means for a four-high rolling mill according to claim 7, in which the backup roll-changing truck is slidably mounted on pedestals on the base so as to be transversely moved by the hydraulic cylinder in the direction perpendicular to the roll axis.

9. Roll-changing means for a four-high rolling mill in accordance with claim 8, in which said backup roll-changing truck is provided with a sliding surface for carrying the backup rolls for sliding movement in the direction of roll axis and a plurality of rails for carrying the working roll-changing truck for movement in the direction of roll axis.

10. Roll-changing means for a four-high rolling mill in accordance with claim 8, in which the pedestal is provided with a pair of stoppers provided at the opposite sides thereof for limiting the transverse transfer distance of the backup roll-changing truck and a pair of intermediate stoppers which can be selectively moved into and out of the operative position.

11. Roll-changing means for a four-high rolling mill in accordance with claim 1, in which an intermediate pedestal is provided between the rolling mill stand and the backup roll-changing truck for guiding the backup rolls, the intermediate pedestal being so arranged that its upper surface aligns with the lower surface of the sled for the backup roll and the sliding surface on the backup roll-changing truck.

12. Roll-changing means for a four-high rolling mill in accordance with claim 11, in which the sled for the backup roll can be connected with the working roll-changing truck by means of a rotatable hook whereby the working roll-changing truck is rearwardly moved simultaneously when the backup rolls are moved from the rolling mill stand to the backup roll-changing truck.

13. Roll-changing means for a four-high rolling mill in accordance with claim 5, in which the floor plate located rearwardly of the working roll-changing truck is vertically movable, the floor plate being moved upwardly to provide a space for receiving the working roll-changing truck.

14. Roll-changing means according to claim 9, in which said transfer means comprises means for axially moving the top and bottom working rolls and means for axially moving the top and the bottom backup rolls and wherein said traction car includes an electric motor and a mechanism for transferring the rotation of the motor, a pinion shaft in the mechanism being arranged to engage with racks provided on the working roll-changing truck and a floor plate.

15. Roll-changing means according to claim 14, in which the pedestal is provided with a pair of stoppers provided at the opposite sides thereof while limiting the transverse transfer distance of the backup roll-changing truck and a pair of intermediate stoppers which can be selectively moved into and out of the operative position, and in which the floor plate located rearwardly of the working roll-changing truck is vertically movable the floor plate being moved upwardly to provide a space for receiving the working roll-changing truck.

16. Roll-changing means according to claim 15, in which an intermediate pedestal is provided between the roll mill stand and the backup roll-changing truck for guiding the backup rolls, the intermediate pedestal being so arranged that its upper surface aligns with the lower surface of the sled for the backup roll and the sliding surface on the backup roll-changing truck.

17. Roll-changing means according to claim 16, in which the sled for the backup roll is connectable with the working roll-changing truck by means of a rotatable hook, whereby the working roll-changing truck is rearwardly moved simultaneously when the backup rolls are moved from the rolling mill stand to the backup roll-changing truck.
